CREAM JUG

James I. Thompson, Vancouver, British Columbia, Canada

Application March 15, 1954, Serial No. 29,542

Term of patent 3½ years

(Cl. D44—21)

FIG. 3.

FIG. 1.

Figure 1 is a perspective view of a cream jug, showing my new design.

Figure 2 is a sectional view taken through the rim portion and showing in elevation the front face of the pouring spout.

Figure 3 is a plan view thereof.

I claim:

The ornamental design for a cream jug, as shown.
